ELECTRICAL OUTLET TRAINING DEVICE

Jack N. Holcomb, Fort Lauderdale, Fla., assignor to
National Intelligence Academy

Filed Oct. 30, 1974, Ser. No. 519,067

Term of patent 14 years

Int. Cl. D19—07

U.S. Cl. D19—62

FIG. 1

Fig. 2

FIG. 3

FIG. 1 is a perspective from the front of an electrical outlet training device showing my new design;

FIG. 2 is a reduced perspective from the rear; and

FIG. 3 is a plan view from the top.

I claim:

The ornamental design for an electrical outlet training device, as shown.
